UNITED STATES PATENT OFFICE

WILLIAM CAMERON, OF CHICAGO, ILLINOIS, ASSIGNOR TO CAMERON CAN MACHINERY CO., OF CHICAGO, ILLINOIS, A CORPORATION OF ILLINOIS

COMBINED FORMING AND THREAD-ROLLING MECHANISM FOR CAPS

Application filed March 23, 1927. Serial No. 177,525.

This invention relates to mechanisms for manufacturing sheet metal caps in general and more particularly to a combined cap forming and cap thread rolling machine.

5 Heretofore in manufacturing caps where in addition to the cap forming operation a subsequent operation such as rolling the thread on the cap which took a much longer time than the forming operation was involved, much delay and lost motion was experienced between the two operations because the mechanism for forming the cap and the mechanism for performing the subsequent operation were not connected together for continuous and automatic operation.

10 It is, therefore, the principal object of this invention to provide a mechanism for manufacturing caps in which the caps discharged from the forming mechanism are automatically fed to the mechanism for subsequently operating upon them such as the thread rolling mechanism.

15 The cap forming mechanism is for mechanical reasons ordinarily capable of turning out unfinished caps much faster than a single thread rolling or like device can complete its work on the caps thus turned out.

20 It is accordingly another object of this invention to provide a construction whereby the caps from the cap forming mechanism are fed automatically to a plurality of cap thread rolling or like devices, thus enabling the forming mechanism to be run at its best speed and the entire combination to be run without any lost motion or delay between the cap forming and the cap thread rolling devices.

25 It is also an important object of this invention to provide an efficient feeding mechanism for receiving caps or the like from one mechanism and distributing them in predetermined proportions to a plurality of devices adapted to perform a subsequent operation on said caps.

30 Other and further objects of this invention will be apparent as the same becomes better understood from an examination of the specification and claims in connection with the accompanying drawings, wherein:

Fig. 1 is a fragmentary longitudinal elevation partly in section illustrating a combined cap forming and cap thread rolling mechanism embodying this invention,

Fig. 2 is a plan view partly in section of the same,

Fig. 3 is an enlarged fragmentary detail longitudinal elevation view showing the distributing mechanism,

Fig. 4 is a section taken at the line 4—4 of the Fig. 3.

Referring to the drawings more particularly, numeral 5 designates the base of a cap forming mechanism of any suitable type adapted to turn out sheet metal caps of substantial cylindrical form and closed at one end. An example of this general type of machine is disclosed in my former Letters Patent No. 1,477,240 granted December 11, 1923. The caps are discharged from the dies onto a chute 6.

70 In this instance the caps which are turned out by the forming machine 5 are, as previously stated, of cylindrical form and closed at one end and require a subsequent thread rolling operation to be performed upon them. The thread rolling operation requires considerably more time than does the blanking and forming operation and for this reason a single thread rolling device cannot ordinarily take care of the normal output of the forming mechanism. Accordingly I provide a plurality, in this illustration two, of thread rolling machines 7 and 8, respectively, and connect them as will be hereinafter described with the forming mechanism in such a manner that the caps discharged by the latter mechanism in unfinished form will be automatically delivered in proper predetermined proportions to the individual thread rolling devices according to their respective capacities. The capacity of the forming mechanism is substantially twice that of either of the two thread rolling mechanisms.

75 To effect the aforementioned automatic delivery of the caps from the forming mechanism to the two thread rolling machines I provide a conveyor including a frame provided with vertical elements 9 and 11 supported near the base of the respective thread

rolling machines 7 and 8. The frame of the conveyor also includes a pair of spaced parallel longitudinal elements 12 secured to the upper ends of the elements 9 and 11 and 5 extending to the frame 13 of the forming machine, the ends of said elements 12 being secured to a transverse rod 14 extending across an opening 15 in said frame. A conveyor belt 16 extends from within the frame 13 beneath the chute 6 out of the opening 15 and 10 between the elements 12 and is carried at one end by a driving roller 17 transversely journaled in the frame 13 and at its other end by a transverse roller 18 carried by said elements 12. A third roller 19 is provided intermediate the ends of the belt 16 is carried by the elements 12 for supporting the upper portion of said belt and divides said portion into a horizontal portion 21 and a gradually 15 sloping portion 22 leading through the opening 15 from the chute 6. A fourth roller 23 is rigidly secured on a transverse shaft 24 journaled in the frame 13 just inside the opening 15 and acts to maintain tension on 20 the belt 16 by bearing against the lower portion of said belt.

The conveyor is driven so that its upper portion as viewed in Figs. 1 and 2 moves continuously to the right carrying with it the 30 caps discharged from the cap forming mechanism. The thread rolling machines 7 and 8 may each be of the type represented generally by my co-pending application Serial No. 653,059 for cap thread rolling machine, 35 filed June 23, 1923, which has matured into Patent No. 1,639,367 issued Aug. 16, 1927 and are provided with intake chutes 25 and 26, respectively, extending to the edge of said conveyor whence they are adapted to receive 40 caps upon which they are to perform a subsequent operation.

In order to apportion the caps to the two thread rolling machines 7 and 8 in accordance with their respective capacities which 45 in this case are the same, I provide a distributing mechanism which will now be described. The caps being delivered to the conveyor are carried substantially along the center line thereof at longitudinally spaced 50 intervals. These intervals will be substantially the same regardless of fluctuations in the speed of the discharge of the caps because the driving roller 17 of the conveyor being mounted on the drive shaft of said machine, 55 said shaft will vary the speed of the conveyor in the same proportion as that of the machine. A disk 27 is rigidly mounted on the shaft 24 and is provided on its side face with a cam surface 28, the same being de- 60 pressed for one-half of each rotation of the shaft 24 and elevated for the remaining one-half. A lever 20 on a shaft 29 journaled in a bracket 31 secured to the frame 13 is provided with a roller 32 at its outer end which 65 is held up against the surface 28 by a spring

33. A second lever 30 also rigid on the shaft 29 is connected by means of a rod 34 to an arm 35 secured at the upper end of a shaft 36 journaled in a bracket 40 on the rod 14. A movable guide 37 for the caps is secured 70 to the lower end of the shaft 36. The guide 37 is comparatively wider at its intake end 38 than at its discharge end 39 and is adapted to receive the caps between its converging sides 41 as said caps are carried along by the 75 conveyor. The guide 37 is connected at its intake end 38 with the shaft 36 so as to oscillate with said shaft to move the discharge end 39 from one side of the conveyor to the other upon each oscillation of said shaft. Since 80 the cam surface 28 is designed to elevate the roller 32 for the same length of time that it depresses said roller the oscillations of the shaft 36 will be such that the guide 37 will deliver caps in substantially equal 85 numbers on each side of the conveyor belt. The conveyor belt is divided beyond the guide 37 by means of a partition 42 into two 90 passages 43 and 44, respectively, the passage 44 leading to the chute 25 of the first 95 thread rolling machine 7 and the passage 43 leading beyond the machine 7 to the chute 26 of the second thread rolling machine 8. Suitable side walls 45 are supported along the edges of the upper portion of the belt so 100 as to prevent the caps from falling off the sides of said belt.

In operation the forming mechanism is allowed to run at its regular speed discharging 100 caps to the chute 6 whence they are dropped on to the center of the conveyor. Since the conveyor is driven from the main shaft of the forming mechanism the spacing of the caps on the conveyor will be substantially 105 constant regardless of any variations in speed of said mechanism. The guide 37 will 110 oscillate as previously described to deflect the caps from the center of the conveyor, the caps passing out of the discharge end 39 of said guide to form two transversely spaced 115 parallel lines of caps one near each edge of the conveyor instead of the one single line of caps at the center of the conveyor. Since the discharge end 39 of the guide 37 is held the same length of time near one edge of the conveyor as the other, the two lines of caps resulting therefrom will be of substantially 120 equal numbers. One of the two lines of caps thus formed will pass to the cap thread rolling machine 7 and the other line of caps 125 will pass to the other thread rolling machine 8 where the threads are automatically rolled on the caps.

With the foregoing arrangement the caps may be completed at a high rate of speed, 125 the two thread rolling machines by their combined operations keeping up with the capacity of the cap forming machine while the latter is run at unreduced speed.

I am aware that many changes may be 130

made without departing from the principles of this invention and I do not wish to be limited to the details shown or described.

I claim:

5. 1. The combination of a cap forming mechanism adapted to discharge unfinished caps, a plurality of thread rolling devices of predetermined capacities adapted to roll threads on said caps, and means for automatically dividing the caps discharged from said mechanism and feeding them to said devices in accordance with their capacities.

10 2. The combination of a cap forming mechanism adapted to discharge unfinished caps, a plurality of thread rolling devices adapted to roll threads on said caps, and means for automatically dividing the caps discharged from said mechanism and feeding them to said devices in predetermined amounts.

15 3. In a mechanism of the class described, the combination of a conveyor, a mechanism adapted to discharge unfinished articles to said conveyor and operatively connected to the conveyor for driving the same, a plurality of devices adapted to receive said articles from the conveyor and perform a subsequent operation upon the articles and means for dividing said articles as they pass along said conveyor and for directing the articles 20 in predetermined proportions to said devices.

25 4. In a mechanism of the class described, the combination of a conveyor, mechanism adapted to discharge unfinished articles to said conveyor whereby upon the continuous movement of the conveyor the articles are carried in line on the conveyor, a plurality of devices adapted to receive said articles from the conveyor and perform a subsequent operation upon the articles, and a guide member movable over said conveyor for dividing 30 said line of articles into a plurality of lines of predetermined numbers of articles.

35 5. In a mechanism of the class described, the combination of a conveyor, a mechanism adapted to discharge unfinished articles to said conveyor, means for driving said mechanism and simultaneously operating said conveyor, a plurality of devices adapted to receive said articles from the conveyor and 40 perform a subsequent operation upon them, and means operable in accordance with the travel of the conveyor for dividing said articles as they pass along the conveyor and for directing the articles in predetermined 45 proportions to said devices.

55 6. In a mechanism of the class described, the combination of a conveyor, mechanism adapted to discharge unfinished articles to said conveyor whereby upon the continuous movement of the conveyor the articles are carried in line on the conveyor, a plurality of devices adapted to receive said articles from the conveyor and perform a subsequent 60 operation upon the articles, and a movable guide member driven by said conveyor for 65

dividing said line of articles into a plurality of lines of predetermined numbers of articles.

7. In a mechanism of the class described, the combination of a conveyor, mechanism adapted to discharge unfinished articles to 70 said conveyor whereby upon the continuous movement of the conveyor the articles are carried thereon, a plurality of devices adapted to receive articles from the conveyor and perform a subsequent operation upon the articles, means for apportioning the articles on the conveyor for the respective devices, and means for delivering the articles thus apportioned to each of the respective devices 75 in a plane at an angle to that of the conveyor.

8. In a mechanism of the class described, the combination of a conveyor, cap forming mechanism adapted to discharge unfinished caps to said conveyor whereby upon the continuous movement of the conveyor the caps 80 are carried thereon, a plurality of devices adapted to receive caps from the conveyor and perform a subsequent operation upon the caps, means for apportioning the caps on the conveyor for the respective devices, 85 and means for delivering the caps thus apportioned to each of the respective devices in a plane at an angle to that of the conveyor.

In witness of the foregoing I affix my signature.

WILLIAM CAMERON.
